CAR DOOR LOCKING MECHANISM

George B. Dorey, Westmount, Quebec, Canada,
assignor to Enterprise Railway Equipment
Company, Chicago, Ill., a corporation of Illinois

Application June 5, 1947, Serial No. 752,761

1 Claim. (Cl. 105—308)

1

My invention relates to an improved car door locking mechanism for use in connection with the doors of railway hopper cars and the like.

A particular object of my invention is to provide a mechanism suitable for use in connection with vertically swinging doors employed in hopper cars and is especially adapted for use in connection with so called unit doors which are swung to closed position manually and thereafter latched in closed position.

One of the particular objects of my invention is to provide a mechanism with the weight thereof so distributed in relation to the door structure that the weight of the parts will only be lifted a limited vertical distance in the course of the door closing operation.

My invention further resides in certain details of construction and arrangements of parts such as will be more fully pointed out hereinafter and claimed.

For further comprehension of my invention, reference may be had to the accompanying drawings wherein:

Fig. 1 indicates a transverse sectional view of a portion of a so called W type of hopper car, showing in elevation, with the door in open position my improvements in connection therewith. Fig. 2 is a side elevational view of that portion of the car shown in Fig. 1. Fig. 3 is a plan sectional view taken through the door and on a line corresponding substantially to a line 3—3 of Fig.

1. Fig. 4 is a fractional sectional view on an enlarged scale through one of the crank shaft supporting brackets, showing a portion of the crank-shaft in threading relation with the bracket, said section being taken on a line corresponding substantially to a line 4—4 of Fig. 1. Fig. 5 is a side elevational view on an enlarged scale of that portion of the car illustrated in Fig. 1, said view illustrating the door in closed position. Fig. 6 is a side elevational detached view of the outer keeper. Fig. 7 is a frontal elevational view of the outer keeper shown in Fig. 6 as viewed from right to left. Fig. 8 is a side elevational detached view of the inner keeper. Fig. 9 is a frontal elevational view of the inner keeper shown in Fig. 8 as viewed from right to left.

In said drawings, 10 denotes one of the beams of the centersill and 11 one of the side walls of the car. As customary in the type of car shown, the hoppers are disposed on each side of the centersill and extend between the side wall and centersill of the car in transversely aligned relation. Each of said hoppers is defined by a sloping floor wall 12, a substantially vertical inner wall 13

2

and an outside hopper wall 14, the latter sloping inwardly and downwardly towards the longitudinal center of the car.

The hopper adjacent the opening is reinforced by a frame 15 which extends around the side walls and bottom floor wall of the hopper, said frame is preferably of angle shape with one flange 16 overlying the hopper walls and having the adjacent flange 17 outstanding from the said overlying wall. Said frame adjacent the upper part of the hopper is provided with a top member 18 having hinge butts 19 associated therewith. The said frame and edge portions of the hopper walls combine to define the boundaries of a discharge opening which is adapted to be closed by a discharge door 20.

Said door 20 is provided with hinge straps 21 whereby the door is pivotally supported from hinge butts 19 by means of hinge pivots 22 and 23. The door is thus mounted to swing freely in a substantially vertical position when open as indicated in Fig. 2. Said door is preferably formed of sheet metal and is flanged upwardly at 23 at its marginal edges to provide a pan shaped structure which is adapted to embrace the overlying flange of the frame when the door is in closed position. Inwardly of said upwardly extending flanges, the door is provided with a flat seating surface 24 which is adapted to register with the edge portions of the hopper walls when the door is closed.

Inwardly of the flat seating surface 24, the door is provided with a depressed embossment which extends outwardly from the door margins for a considerable depth and operates as a reinforcing member to stiffen the door. Said embossment is in the form of a pan with the bottom wall 25 extending in the general direction of the door and spaced from the seating surface 24 of the door and the sides of said pan shaped structure being indicated at 26, 27, 28 and 29. In its preferred form the embossment is made sufficiently large to take in as much of the door area as possible in order to attain large cubical carrying capacity. The disposition of the major portion of the weight of the door below the level of the marginal abutting portions of the door is of advantage in the raising of the door to closed position. It will be noted by reference to Fig. 5 that the door when in closed position lies at an angle to the vertical and that the main portion of the door as represented by the pan shaped portion lies in a more perpendicular plane than the abutting marginal portion 24 and consequently the

raising operation of the door is a comparatively easy matter.

The door is adapted to be kicked or swung to closed position manually and is retained in closed position by door locking mechanism which includes a crankshaft 30 carried by the door and co-operating keeper means carried by the hopper as indicated at 31 on the inner side of the hopper and at 32 on the outer side of the hopper. Said crankshaft 30 includes a main body portion 33 lying outwardly of the embossment and is pivotally mounted in brackets indicated at 34 and 35 respectively, said brackets in turn being mounted on the embossment.

The crankshaft 30 at each end thereof and outwardly of the supporting brackets is provided with a crank portion including an arm 36 and an outstanding projection 37 in the form of a trunnion. The said arms 36 straddle the door and the weighted portion of the arms and associated trunnions 37 operate to maintain the arms in normal latching position so that the mechanism will always be in readiness to function in the manner of an automatically engageable latch as the door is moved to closed position. The shaft supporting brackets 34 and 35 are mounted at the respective ends of the embossment and are each formed with oppositely directed open bearings 38 and 39 spaced lengthwise of the shaft to provide an elongated aperture 40 disposed between said respective bearings and through which the bent portions 41 of the crankshaft may be threaded as indicated in Fig. 4. The function of bearing 38 is to prevent outward movement of the shaft and the function of bearing 39 is to provide a rigid bearing support for the shaft beyond the limits of the embossment. Each said bracket includes angularly related walls as indicated at 42 and 43 respectively for attachment to the respective walls 25 and 26 of the embossment by means of rivets 44.

The outer bracket 34, which is located adjacent the sloping wall of the hopper, is provided with an end wall 45, said wall 45 being disposed in a plane substantially normal to the pivotal axis of shaft 30; said wall 45 is adapted to act as a guide for the adjacent arm 36 of the crankshaft throughout its entire range of swinging movement and also operates to limit inward longitudinal movement of the shaft. Outward longitudinal movement of the shaft is prevented by a strap plate 46 which is spaced from the wall 45 a sufficient distance to accommodate the associated arm 36 between said respective walls. The plate 46 is secured to wall 45 by means of rivets 47.

The plate 46 is maintained in spaced relation with respect to wall 45 by means of ferrules 48 and 49, said ferrule 48 in addition to its function as a spacer also operating as a stop to limit downward movement of the related arm 36. The ferrule 49 is located at the upper portion of the strap and forms a pivotal support for a locking dog 50, said dog being adapted to be swung into locking engagement with the crankshaft arm to thereby lock the mechanism in operative latching position. The said dog 50 is pivotally mounted at a location so related to the underside of the door as to permit the placement of the said dog rearwardly of the door seating portion 24 and to this end the strap plate 46 is set at an upwardly and rearwardly inclined angle thereby allowing ample swinging operating space for the dog.

The shouldered keepers 31 and 32 which are mounted on the car hopper for co-operating engagement with the trunnion portions 37 of the

crankshaft have their respective shoulders 51 disposed in transversely aligned relation. Said keepers are preferably of angle shape construction with one wall as indicated at 52 overlying and secured to the outstanding flange 17 of the frame and having the other wall consisting of a plate like body construction as indicated at 53 in the case of the outer keeper 32 and 54 in the case of the inner keeper 31. Said respective body portions 53 and 54 lie in planes substantially parallel with the adjacent side walls of the hopper and are spaced therefrom a sufficient distance to accommodate the upwardly extending door flange and the adjacent arm 36.

15 The body portion 54 of the inner keeper 31 is disposed in a plane normal to the axis of the shaft 30 and is formed with a secondary supporting shoulder 55 lying outwardly of and beyond the main supporting shoulders 51, said secondary shoulder being for the purpose of supporting the door in partially closed position. Said secondary shoulder 55 is connected with the main supporting shoulder 50 by a wall 56 extending at an incline between said main and secondary shoulders. Beyond the secondary shoulder 55 the body portion 54 is provided with a forwardly projecting extension presenting an edge surface 57 constituting a downwardly inclined runway leading from the tip of said shoulder 55 and adapted 30 to engage the trunnion portion 37 of the shaft as the door is moved to closed position.

Movement of the door in a closing direction brings the trunnion 37 of the arm 36 at the inner side of the door into contact with the surface 57 thereby displacing the latch from its normal latching position. Continued movement of the door in a closing direction finally results in the associated trunnion dropping into engagement with the secondary shoulder 55 and the door 40 is then retained in partially closed position entirely by the inner keeper 31 and independently of the outer keeper 32.

The door may be moved from its partially closed to fully closed position by movement of the shaft 45 arms 36 in a downward direction, and to this end a fulcrum plate 58 is welded or otherwise secured to the outstanding flange 17 of the frame 16 adjacent the outer supporting keeper, said plate being adapted to serve as a fulcrum for a 50 removable bar as will be described.

Assuming that the door is in partially closed position as indicated in Fig. 2 by conventional dot and dash lines, the closing operation is effected by inserting a bar 59 between trunnion 37 and fulcrum 58 and bearing upwardly as indicated at 60 which results in forcing the trunnion portion 37 at the inner keeper downwardly along inclined surface 56 and wedging the door to closed position.

60 The outer keeper 32 is provided with a laterally extending projection 61 for co-operation with a removable bar 62 whereby the latch may be conveniently and safely released by an operator standing at the side of the car. Said fulcrum 65 extension 61 may also be employed in the course of the door raising operation for levering the door to fully closed position by inserting a suitable tool between the fulcrum 61 and the trunnion 37 and exerting pressure in a door closing direction.

70 It will be noted that the main portion of the shaft indicated at 30, together with the associated supporting bearings only lift a short vertical distance as indicated at 63 in the course of the door raising operation and this feature is a 75 factor which contributes to ease of door operation.

An advantageous feature of my improved construction resides in the fact that the latching mechanism is substantially contained within the plane of the outer hopper side wall and also within the plane of the side flange of the door with the exception of a slightly projecting portion of the crank 37 and this absence of clumsy projecting parts beyond the hopper is a most desirable condition.

What I claim is:

In a car door mechanism for the hopper of a car body having a discharge opening and a door pivotally mounted adjacent the upper part of the opening for closing said opening; the improvement which consists of latching means for retaining the door in closed position, said means including members respectively carried by the door and car body, said members on the door including a crank shaft pivotally mounted adjacent the swinging edge of the door and having an arm at each end thereof formed with a projection extending lengthwise of the shaft and spaced appreciably from the pivotal axis of the shaft, said

members on the car body including shouldered keepers co-operating with the projections of the shaft; brackets on the door for supporting the shaft, one of said brackets having a pair of guiding walls associated therewith, said walls being spaced apart to accommodate one of the arms therebetween; and a locking dog pivotally mounted between said walls and adapted to engage the related arm for locking the door mechanism in operative latching position.

GEORGE B. DOREY.
